UNITED STATES PATENT OFFICE.

GEORGE H. REVELLE, OF SEATTLE, WASHINGTON.

TELEPHONE DIAL-SETTING APPARATUS.

Application filed July 1, 1924. Serial No. 723,455.

This invention relates to dial setting appliances for automatic telephone instruments, and specifically to an improvement in the dial setting devices illustrated and described in my application, Serial No. 713,080, filed May 13, 1924; and its object is to simplify the invention, and generally to render the device more convenient and efficient in operation.

10 In the accompanying drawing,—

Figure 1 is a view in side elevation showing a dial-setting device embodying my improvement applied to a telephone instrument. Fig. 2 is a view partly in vertical section and partly in side elevation of the dial operating device, with the dial and the casing for the controlled mechanism shown in side elevation. Fig. 3 is a horizontal sectional-plan view taken on broken line 3—3 20 of Fig. 2. Fig. 4 is a top plan view of the cap member of the device.

In said drawing, the reference numeral 10 represents a telephone instrument of the automatic type, so called, which is equipped 25 with switching mechanism which is regulated through the medium of a disk, or dial, 11, mounted for rotation above a casing 12.

As best shown in Fig. 3, the dial 11 is provided with a series of eight apertures 13 through which may be seen symbols such, for example, as alphabetic letters 14 and digits 15 provided upon the upper surface 30 of the casing 12.

The above described parts are similar in 35 construction and arrangement to known devices hitherto in use, and the operation of the same may be briefly described as follows:

To make a telephonic connection or "call" 40 as ME4419 for instance, the operator first places his finger in a hole of the dial through which the letter M is seen and then rotating the dial by his finger until the latter encounters the finger-stop which is omitted from 45 the drawing. The operator's finger is then removed from the dial which is thereupon returned to its normal position by means of a spring (not shown) hereinafter termed the return spring, provided within the casing 12. The operator proceeds in the same 50 way with respect to the dial pertaining to the remaining letter E and the digits 4—4—1—9 of the desired "number".

According to the present invention there 55 is secured to the casing, as by means of a clamping screw 18, a cap 20 having a top

wall 21 upon which is marked or printed a series of index symbols such as the letters 14¹ and numerals 15¹ (Fig. 4) for instance, corresponding in kind but in reverse arrangement to the symbols 14 and 15 provided on the casing 11.

Located axially of the cap wall 21 is an arbor 22 for which is provided a journal box which may be formed integral with the cap or, as shown in Fig. 2, comprising a tubular member 23 secured to said wall.

Rigidly secured to the upper end of the arbor 22 and extending radially therefrom is an arm 26 which is provided, preferably, with a finger engaging element 27 and together constituting a crank handle. To the lower end of said arbor, interiorly of the cap 20, is an arm 28 which is arranged radially, or nearly so, from said arbor and carries at 75 its outer end a stud 29 which extends downwardly into one of the apertures 13 of the dial 11. The arm 28 and its stud 29 constitutes what may be termed a crank arm, the same being in continuous and positive engagement with the dial 11.

The index symbols 14¹ and 15¹ are located circumferentially upon the cap 20 and with regard to the respective symbols 14 and 15 on the casing 12 so that the handle 26 must be turned clockwise to a predetermined index symbol instead of from a symbol to a finger stop when employing the dial directly as hitherto. More particularly, in place of the operator being required to utilize his finger in a suitable aperture that denoted, for example, by symbol "7" (Fig. 3) and then turning the dial until the finger is arrested by encountering the stop above mentioned, the operator simply turns the handle 26 clockwise until it registers with the index symbol "7" (Fig. 4), and so on for the successive integers of a call.

The operator releases the handle between each setting movement to permit the dial to rotate counter clockwise to its normal position.

The invention is extremely simple in its construction, comprising few parts which are not liable to become deranged and is convenient to use.

What I claim, is,—

1. In apparatus of the class described, the combination with a rotary dial, a stationary cap enclosing the same, an arbor journaled in said cap, a crank secured to said arbor below said cap and positively engaged in

the dial for unitary movement therewith in either rotary direction, a handle secured to the arbor above said cap for effecting rotary movement to the dial, and index characters provided on the cap for indicating the distances the handle is to be swung to turn the dial into predetermined rotary positions.

2. In a telephone-dial setting apparatus, the combination with the rotary dial having a series of holes therein, a cap enclosing said dial and rigid with the telephone instrument, an arbor journaled in said cap in axial alignment with said dial, an arm secured to said arbor below said cap, said arm having a stud element continuously engaging the dial in one of the holes thereof, an operating handle secured to the arbor exteriorly of the cap, and index characters pro-

vided on said cap whereby the turning of the handle is regulated for setting the dial into predetermined rotary positions.

3. In apparatus of the class described, a rotary dial, a stationary cap enclosing said dial and provided with a series of circumferentially disposed index characters, and a crank continuously coupled with the dial and turnable therewith as a unit about its axis of motion for rotating the dial into positions determined by said crank with respect to said index characters whereby the dial is set into predetermined rotary positions.

Signed at Seattle, Washington, this 25th day of June, 1924.

GEORGE H. REVELLE.
